[57] **CLAIM**

The ornamental design for a scale, as shown and described.

DESCRIPTION

The file of this patent contains at least one drawing executed in color. Copies of this patent with color drawings will be provided by the patent and trademark office upon request and payment of the necessary fee.

FIG. 1 is a top plan view of a scale showing my new design; FIG. 2 is a side elevational view of one side thereof, the opposite side being a mirror image thereof;

FIG. 3 is a perspective view of the top, front and one side thereof;

FIG. 4 is a perspective view of the bottom and one side thereof;

FIG. 5 is a perspective view of the top and rear thereof; and, FIG. 6 is a perspective view of the top and front thereof.

The support surfaces are not part of the claimed design and are hereby disclaimed.
